LUGGAGE CASE

Samson Gorky, New Castle, Pa., assignor to
Airway Industries Incorporated

Filed July 15, 1974, Ser. No. 488,651

Term of patent 14 years

Int. Cl. D3—01

U.S. Cl. D87—5 F

Fig.4.

Fig.5.

Fig.6.

Fig.2.

Fig.1.

Fig.3.

FIG. 1 is a side elevational view of a luggage case showing my new design, the opposite side being similar;

FIG. 2 is a top plan view thereof;

FIG. 3 is a bottom plan view;

FIG. 4 is an end elevational view;

FIG. 5 is an elevational view of the other end; and

FIG. 6 is a top perspective view.

I claim:

The ornamental design for a luggage case, as shown and described.
